UNITED STATES PATENT OFFICE.

HARRY W. URICK, OF SEATTLE, WASHINGTON.

LIQUID DISPENSER.

Application filed May 16, 1922. Serial No. 561,334.

To all whom it may concern:

Be it known that I, HARRY W. URICK, a citizen of the United States of America, and resident of the city of Seattle, in the county of King and State of Washington, have invented certain new and useful Improvements in Liquid Dispensers, of which the following is a specification.

My invention relates particularly to a dispensing apparatus intended for dispensing such materials as catsup, which is generally a rather heavy liquid and which does not flow freely.

The object of my invention is to provide means whereby a measured individual charge of catsup may be trapped and then positively ejected from a container.

Another object is to provide a dispenser of this character which may be connected to the usual standard catsup containers.

A further object is to provide simple and reliable means for effecting the trapping and ejection of an individual charge.

A further object is to provide a dispenser which is of simple and inexpensive construction and which will be reliable in operation.

A further object is to provide a dispenser which may be supported above the average level of the liquid, to permit drainage therefrom into the liquid container.

My invention comprises those novel parts and combinations thereof which are shown in the accompanying drawings, described in the specification and particularly defined by the claims terminating the same.

In the accompanying drawings I have shown my invention in the form which is now preferred by me.

Figure 1 is an axial section through a catsup container and my dispenser showing the latter secured upon the container.

Figure 2 is an enlarged section similar to Figure 1, showing a detail of the dispenser.

Figure 3 is a section on line 3-3 of Figure 2.

Figure 4 is an enlarged section on line 4-4 of Figure 1, showing a portion of the dispenser.

I secure a tube 1, which to distinguish it from other tubes, may be called the inner tube, within suitable mounting or securing means, such as the cap 10 which may be screwed or otherwise secured upon the end of the ordinary catsup bottle or container C. The tube 1 extends inward from the cap 10

within the neck of the bottle, but preferably not to the bottom of the bottle, and also preferably extends for a short distance outward of the cap. It is divided between its ends by a diaphragm 11 and a delivery spout 12 communicates with the space beneath the diaphragm 11, being shown herein as extending through the diaphragm. A lateral delivery outlet 13 is formed on the upper end 65 of the spout 12.

At its inward end, being that end within the bottle and inward of the diaphragm, the tube 1 is ported, ports 14 being shown. Through these ports communication is 70 established with the interior of the container C. An outer tube 2 is slidable upon the inner tube 1, and this tube likewise is provided with ports 24 which are normally in registry with the ports 14. When moved 75 lengthwise, however, over the inner tube 1, the outer tube 2 will close the ports 14 and thus a charge of material will be trapped within the inward portion of the inner tube.

A plunger 3 is movable through the inner tube 1. To effect movement of the plunger I have shown a stem 31 which projects outward through the diaphragm 11 and which has secured to its outward end a flexible tension member 32. This tension member 80 passes over several guides 33, which reverse it in direction and then again reverse it into its original direction. Its free end is secured to a rod 34 guided in a fixed guide 35 and having a push button 36, preferably 85 likewise guided upon a guide 37. Movement of the push button 36 will effect movement of the plunger 33 in the same direction, to eject a charge. The plunger is returned to normal position by the action of a spring 37 90 bearing upon a collar 38 secured to the outward end of the stem 31.

I provide means actuatingly connecting the plunger 3 and the outer tube 2 whereby 100 upon movement of the plunger 3 in the direction to eject a charge, the outer tube 2 is automatically moved in a direction to close the ports 14, and vice versa. The means which I have shown for accomplishing this comprise a bar 30, preferably toothed upon opposite sides, and projecting from the rear side of the plunger 3 to which it is connected, and a pair of levers 4 which are pivoted between their ends upon the inward end of the inner sleeve 1 or upon ears 16 105 projecting therefrom. The inner end of the levers 4 are formed to engage the teeth of

the bar 30. In their outer ends is secured a transverse pin 41 which is embraced by a pair of U-brackets 42 secured to the outer tube 2. I have shown a guide 26 carried by 5 the inward end of the outer tube 2 to receive the toothed bar 30 and to prevent its rotation.

In order to expel a charge of catsup from the container C the container is inverted to 10 permit the catsup to run into the inner tube 1, through the ports 14. Preferably while the container is still held in inverted position the push button 36 is moved upward in the position shown in Figure 1, or down- 15 ward in the pouring position of the container. This initiates movement of the plunger 3 through the flexible tension member 35 and the stem 31 in opposition to the spring 37.

20 At the beginning of this movement the levers 4 are in the position shown in Figure 1 and the ports 14 and 24 are in registry. The movement of the rack bar 30 causes positive engagement of its teeth with the 25 inner ends of the levers 4, and these are moved into the position shown in Figure 2. During this movement engagement of the pins 41 with the U-brackets 42 effects movement of the outer tube 2 sufficiently to close 30 the ports 14. When the ports 14 reach closed position the levers 4 reach such a position that they no longer engage the teeth of the bar 30 but act as ratchet pawls to permit continued movement of the bar 30 and of the 35 plunger 3.

Continued movement of the plunger 3 through the closed trap formed within the tube 1 expels the charge from the trap 40 through the delivery spout 12. When sufficient of the material has been expelled the push button 36 is released and the action of the spring 37 effects a return of all parts to their normal position. At the beginning of the return movement the inner ends of the 45 levers 4 again engage with the teeth of the bar 30 and the outer tube 2 is reversed in position thereby, and its ports 24 are brought into registry with the ports 14 of the inner tube.

36 What I claim as my invention is:

1. A dispensing apparatus including a 55 pair of members having a plurality of axially spaced ports, and relatively axially movable through a short distance to form a closed trap for an individual charge of the material to be dispensed, and a separate ejector movable through such trap through a greater distance to expel the material.

2. A dispensing apparatus including a 60 pair of members having a plurality of axially spaced ports, and relatively axially movable through a short distance only to form a closed trap for an individual charge of the material to be dispensed, a separate ejector movable through such trap through a

greater distance to expel the material, and means for returning said ejector to its normal position following expulsion of the charge, and for opening the trap-forming members immediately upon the beginning of 70 the return movement of the ejector.

3. A dispensing apparatus including an inner tube and an outer tube slidable thereon, said tubes each having axially spaced 75 ports therethrough, the ports of the two tubes being normally in registry, and the tubes being movable relatively to close said ports, and a separate plunger movable lengthwise within the inner tube through a distance greater than the distance between 80 port centers to expel a charge of material trapped therein.

4. A dispensing apparatus including an inner tube and an outer tube slidable thereon, said tubes each having axially spaced 85 ports therethrough, the ports of the two tubes being normally in registry, and the tubes being movable relatively to close said ports, a separate plunger movable lengthwise within the inner tube through a distance greater than the distance between port centers to expel a charge of material trapped therein, and means connecting said plunger, 90 said inner tube, and said outer tube to move the outer tube to close the ports in the inner tube at the beginning of movement of the plunger in the ejecting direction, and to open such ports at the beginning of movement of the plunger's return movement. 95

5. A dispensing apparatus including relatively movable members adapted to form a closed trap for an individual charge of the material to be dispensed, a separate ejector movable through said trap to expel the material, and means connecting the ejector and the relatively movable members whereby the trap is closed substantially simultaneously with the start of the ejector's movement, said means being yieldable to permit continued movement of the ejector to the end of its travel. 100

6. In a dispensing apparatus, the combination with a cap adapted to be secured upon a bottle, of an inner tube secured to said cap and extending within the neck of the bottle, and terminating in a delivery outlet, an outer tube slidable upon said inner tube, said inner and outer tubes each having ports therethrough normally in registry, means for moving said outer tube to close said ports, and an ejector separate from said tubes and movable through the inner tube to expel a charge of material trapped therein through said delivery outlet. 115

7. In a dispensing apparatus, in combination, a plurality of relatively movable trap-forming members, a separate plunger movable therethrough to eject a charge of material trapped therein, a flexible tension member connected to said plunger, guides 120 125 130

for said flexible member leading it back upon itself and then in the opposite direction, and a push button connected to the end of said flexible member, whereby movement of the push button will cause movement of the plunger in the same direction.

8. In a dispensing apparatus, in combination, a fixed inner and an outer tube having ports normally in registry, the outer tube being movable to close said ports, a plunger movable through the inner tube to eject a charge of material trapped therein, a bar projecting from the rear of said plunger, and means actuatingly connecting said bar and said outer tube whereby ejecting movement of the plunger and bar causes movement of said outer tube to close said ports.

9. In a dispensing apparatus, in combination, a fixed inner and an outer tube having ports normally in registry, the outer tube being movable to close said ports, a plunger movable through the inner tube to eject a charge of material trapped therein, a bar projecting from the rear of said plunger, and a lever pivoted upon the inner tube and actuatingly connected to the outer tube and to said bar, whereby ejecting movement of the plunger and bar effects movement of the outer tube to close said ports.

10. In a dispensing apparatus, in combination, a fixed inner tube and an outer tube having ports normally in registry, the outer tube being movable to close said ports, a plunger movable through the inner tube to eject a charge of material trapped therein, a bar having teeth upon opposite sides thereof and projecting from the rear of said plunger, a pair of oppositely-positioned levers

pivoted between their ends upon the inner tube, their inner ends being engageable with the teeth upon said bar, a pin extending transversely of the outer end of each lever, and U-brackets secured to the outer tube and embracing said pins, whereby beginning movement of the bar effects movement of the outer tube in the opposite direction, substantially as described.

11. In a dispensing apparatus, in combination, a cap adapted to be secured upon a bottle, an inner tube secured to said cap and extending within the bottle, a diaphragm closing said tube between its ends, a delivery spout communicating with the space therein inward of the diaphragm, the inner portion of said tube having ports therethrough, an outer tube slidable over the ported portion of said inner tube and having ports normally registerable with those of the inner tube, a plunger movable through the ported portion of the inner tube to expel a charge of material trapped therein, a stem connected to said plunger and extending through said diaphragm, a spring in the outward portion of said inner tube and engageable with the stem to project it inwardly, a tension member connected to the outward end of said stem, a push-button operatively connected to the other end of said tension member, and means actuatingly connecting said outer tube and plunger whereby ejecting movement of the plunger effects movement of the outer tube to close the ports of the inner tube.

Signed at Seattle, King County, Washington.

HARRY W. URICK.
